UNITED STATES PATENT OFFICE

2,604,917

HANDBAG

William J. Reilly, Attleboro, Mass., assignor to
Evans Case Co., a corporation of Massachusetts

Application January 29, 1949, Serial No. 73,601

1 Claim. (Cl. 150—34)

1

This invention relates to a handbag of the type carried by a woman for containing various articles of utility which are carried by a woman. Handbags have been variously formed heretofore with pockets for containing a purse, mirror, or other articles, which pockets are usually formed as an integral part of the bag and are readily in view that they may be accessible to the user.

One of the objects of this invention is to provide a handbag having a pocket which will be concealed from view in the usual use of the handbag.

Another object of this invention is to provide a handbag which will have a removable unit which is attached to the wall of the handbag and which when in position will conceal the pocket in the wall of the handbag along which it extends.

Another object of this invention is to utilize a part of the attaching means for the removable unit as a part of the closure means for the unit when removed from the bag.

Another object of this invention is to provide a removable unit which in effect is a part of the handbag but which will carry the different useful articles which may be used by a woman, keeping them together in the handbag in an orderly location and which unit may be removed from the handbag that the same articles may be conveniently carried in the unit for evening clothes use, when a smaller unit would be carried by the woman.

Another object of this invention is to provide a removable unit having a wall which may tuck beneath the inwardly folded portion of the bag so that its edges are concealed from view, that it may more effectively hide the pocket in the wall section of the bag along which it extends.

With these and other objects in view, the invention consists of certain novel features of construction, as will be more fully described and particularly pointed out in the appended claim.

In the accompanying drawings:

Figure 1 is a perspective view of the bag in closed position;

Figure 2 is a perspective view with parts of the bag broken away to better show the construction of the novel features of the bag;

Figure 3 is a perspective view of the unit which is contained within the bag as removed therefrom and in open position as it is positioned in the bag; and

Figure 4 is a perspective view of the unit of Figure 3 shown in closed position.

In proceeding with this invention I provide a bag formed of two sections which are hinged together and which may clasp to close the bag. A

web portion which may fold into the interior of the bag usually extends between the sections. Within the bag and along the interior wall of one of the sections I have provided a pocket and also in the bag I have provided a separable unit consisting of spaced walls, one of which is of a height to just contain the articles intended to be held in the unit, while the other wall extends upwardly to a substantial extent beyond the short wall and fits over the inner surface of the section of the bag having the pocket and under the folded-in bellows portion of the section so as to appear as an integral part of the bag, the wall being of such extent as to hide the pocket in the above mentioned section and be attached in the bag to cover this inner surface by some detachable means, a part of which is carried by the upstanding wall of the unit and a part of which is carried by a tab on the bag, the part of the fastening means which is attached to the unit also having a complementary part on the short wall of the unit so as to hold this upstanding wall in covering relation to the unit when removed therefrom.

With reference to the drawings, 10 designates generally the handbag which is provided with handles 11 and 12 attached to sections 14 and 15 of the handbag, each section comprising a metal frame 16, which frames are hinged as at 17 at their opposite ends. Each section also comprises an enclosing wall 18 having inner and outer surfaces with bellows type side walls 19 between these enclosing walls and the frame. There is also a web portion 20 which extends between the frame sections from the hinge upwardly about half way of one of the legs of the metal frame for enclosing the contents of the bag and limiting the opening movement of the section. A clasp designated generally 21 is mounted upon one of the metal frame sections 16 having an operating handle 22 to clasp with the opposite metal frame section 16 and hold the bag in closed position, as shown in Figure 1.

A pocket, provided by a wall 25 the entrance to which is at edge 26, is formed on the inner surface of the enclosing wall 18 of the section 14 and extends from wall 19 to wall 19 the full width of the bag. This pocket is concealed by an insert which comprises a utensil unit 27 (see Figs. 3 and 4) having a front wall 28 and a back wall 29, which walls are connected together by end walls 30 and a bottom wall 31, which bottom wall may be of the same piece of material as the front and back walls. This construction permits of a spacing between the walls 28 and 29 to form a pocket 32 of substantial width for containing different

articles such, for instance, as a cigarette case 33, a lighter 34, a lipstick 35, and a compact 36, while a separate pocket 37 may be provided by means of a shorter wall 38 for the reception of a comb 39 in this auxiliary pocket. When this unit 27 is located in the bag, the back wall 29 thereof extends upwardly covering the inner surface of the containing wall 18 and concealing the pocket 26, the wall 29 being attached to the section 14 of the bag by means of a separable fastener comprising a stud 40 secured on the wall 29 and a socket 41 secured on the inner surface of the tab 42 which is fixed to the wall 18 and extends downwardly over the top marginal edge of the wall 29, thus detachably securing the unit 27 in the bag. 15

If it is desired to remove the unit 27 from the bag, it is merely necessary to unclasp the separable fastener 40 and lift the unit 27 from the bag, thus exposing the concealed pocket 25. If it is desired to use this unit 27 as a separate parcel 20 by itself, the stud portion of the fastener 40 may be brought down into engagement with a socket portion of a fastener 43 which corresponds to the socket 41 so that the wall 29 may act as a cover for the utensils which are positioned within the 25 pocket 32 to maintain them in position.

I claim:

A handbag having a containing wall, a utensil unit in said bag provided with a pair of walls to form a pocket, one of said walls being flexible and of a length to extend over the top of the pocket and along the overlapped other wall to provide a cover for the unit, a fastener to hold the cover closed, comprising one part on the cover and the 30 other part on the wall overlapped, said cover 35

extending upwardly along the wall of the bag, a tab at the upper edge of the wall along which the cover extends carrying a fastener part which is a duplicate of that on the overlapped pocket wall, securing said cover to the wall of the bag section to suspendingly detachably secure said unit thereto with its pocket open whereby said pocket unit may be detached and the unit removed from the bag and closed.

WILLIAM J. REILLY.
